DESIGN FOR A MATTING OR SIMILAR ARTICLE

Carl Mentrup, Brooklyn, N. Y.

Application October 30, 1941, Serial No. 103,950

Term of patent 3½ years

To whom it may concern:

Be it known that I, Carl Mentrup, a citizen of the United States, residing in the Borough of Brooklyn, in the county of Kings and State of New York, have invented a new, original, and ornamental Design for a Matting or Similar Article, of which the following is a specification, reference being had to the accompanying drawing, forming part thereof, wherein the figure is a plan view of a matting or similar article, showing my new design.

I claim:

The ornamental design for a matting or similar article, substantially as shown.

CARL MENTRUP.
